ATTORNEY :-

UNITED STATES PATENT OFFICE.

WILLIAM HENRY PLACE, JR., OF PROVIDENCE, RHODE ISLAND.

BANJO-TONE MODIFIER.

Application filed October 27, 1927. Serial No. 229,198.

My invention has reference to an improvement in banjos and more particularly to an improvement in tone modifiers for banjos.

In the usual modern construction of 5 banjos, the skin head of the banjo is tightly stretched over the metal rim of the banjo. The metal rim increases the volume of sound and it also gives a metallic tone to the instrument.

10 The object of my invention is to provide such a banjo with a tone modifier whereby the metallic or overtones are eliminated.

Another object of my invention is to provide the banjo tone modifier with means for 15 adjusting the tone modifier relative to the skin head of the banjo, whereby the exact tone required may be easily and quickly obtained.

20 My invention consists in the peculiar and novel construction of a banjo tone modifier, said banjo tone modifier having details of construction as will be more fully set forth hereinafter and claimed.

25 Figure 1 is a transverse sectional view through the head of a banjo provided with my improved banjo tone modifier.

30 Figure 2 is a perspective view of the banjo tone modifier, showing the parts in the position they would assume in the head of the banjo.

35 Figure 3 is an enlarged detail sectional view through the banjo head, rim and tone modifier with the greater portion of the banjo head broken away, and

40 Figure 4 is a vertical perspective view of one of the adjusting screw sound deadening tubes, used to prevent metallic vibrations of the screws.

45 In the drawing 5 indicates the head end of a banjo and 6 my improved banjo tone modifier for banjos.

The banjo head end 5 has a metal rim 7 constructed as will be hereinafter described, otherwise the banjo head end 5 has the usual 45 skin head 8 stretched over the metal rim 7 and tightly secured to the rim 7 by the usual hook rods construction 9, as shown in Figures 1 and 3.

50 In carrying my invention into practice I form an internal annular recess 10, in the metal banjo rim adjacent the skin head 8. This recess 10 forms an internal annular shoulder 11 and a comparatively thin rim portion 12 over which the skin head 8 is 55 stretched. A series of screw-threaded holes 13, 13, are formed in the rim an equal dis-

tance apart and at right angles to the skin head 8, the screw-threaded holes terminating outwardly into tubular enlargements 14, 14, as shown in Figures 1 and 3.

60 My improved banjo tone modifier 6 consists essentially of a U shaped circular ring 15 and a series of ring adjusting screws 16, 16. On the bottom of the ring 15 are a series of screw end indentures 17, 17, coinciding with the screw-holes 13, 13, in the banjo rim 7, and the ring 15 forms a circular U shaped trough 18 in which is a ring 19 of felt or other resilient material.

65 The diameter of the ring 15 is less than 70 the recess 10 in the banjo rim 7 and it is held out of contact with the banjo rim 7 by the ring adjusting screws 16, 16, in the screw-threaded holes 13, 13, in the banjo rim 7. The inner ends of the screws 16, 16, enter the 75 screw end indentures 17, 17, in the ring 15 and hold the ring 15 from turning in the banjo head. A sound deadening tube 20 surrounds that portion of each screw 16 in each tubular enlargement 14, 14, in the 80 banjo rim 7, thereby preventing metallic sounds from the screws, caused by chattering or vibrations of the metal screws in the metal rim of the banjo. These sound deadening tubes 20, 20, may be made of felt or 85 other sound deadening materials.

90 When the banjo is in use the tone of the banjo is modified by pressing the felt ring 19 more or less against the inner face of the skin head 8, at the outer periphery of the skin head 8. This is accomplished by adjusting the pressure of the ring adjusting screws 16, 16, on the ring 15, so as to give 95 the required pressure on the felt ring 19.

95 By this construction all of the tones and overtones of the banjo, caused by the vibrations of the skin head of the banjo, are controlled and modified by my improved banjo tone modifier, before they reach the metal rim of the banjo, thereby eliminating metallic tones or overtones from the metal rim 100 of the banjo.

I do not confine myself to the construction shown, as the same could be modified so as to bring the felt ring 19 into contact 105 with the outer face of the skin head 8 and accomplish the same result.

Having thus described my invention I claim as new:—

110 1. In a banjo having a metal rim and a skin head, said metal rim having an annular recess on the inside of the rim, a banjo tone

modifier including a circular ring having a circular groove, a felt ring in the circular groove, said circular ring being in the annular recess in the banjo rim, said felt ring 5 contacting with the skin head of the banjo and means in the banjo rim for adjusting the banjo tone modifier relative to the skin head of the banjo.

2. In a banjo having a metal rim and a 10 skin head, said metal rim having an inner annular recess forming an annular ledge and an annular projecting lip over which

the skin head is drawn, a banjo tone modifier including a circular ring having a **U** shaped trough and a series of screw end indentures, a felt ring in the **U** shaped trough and contacting with the skin head of the banjo, a series of screws screw-threaded through the banjo rim and a felt tube around each screw in the banjo rim, 15 for the purpose as described.

In testimony whereof, I have signed my name to this specification.

WILLIAM HENRY PLACE, JR.
